UNITED STATES PATENT OFFICE.

JULIUS VON KÖNIGSWÄRTER, OF HANOVER, GERMANY.

VESSEL FOR PACKING AND STORING WASHING-POWDERS CONTAINING ALKALINE PEROXIDS.

No. 818,695.

Specification of Letters Patent.

Patented April 24, 1906.

Application filed October 16, 1905. Serial No. 283,060.

To all whom it may concern:

Be it known that I, JULIUS VON KÖNIGSWÄRTER, a subject of the Grand Duke of Saxe-Coburg, residing at Hanover, German Empire, have invented new and useful Improvements in Methods of Packing and Storing Washing-Powder Containing Alkaline Peroxids and Devices Therefor, of which the following is a specification.

This invention relates to a method of packing and storing washing-powder having as a constituent sodium superoxid or other alkali superoxid and a device therefor.

This method consists in the separate compartments containing the constituents composing the washing-powder having such a position relative to one another that the superoxid only encounters the other constituents at the moment of use, when simultaneously with the opening of the packet or vessel the contents of the separate compartments containing the constituents of the washing-powder are mixed.

The excellent properties of alkali superoxid, more particularly sodium superoxid, as a bleaching agent have long been known; but superoxid mixed with soap as a washing material for household use has not been found suitable because owing to the presence of moisture in the soap decomposition of the sodium superoxid is unavoidable. The superoxid must therefore be kept separate and unmixed with the soap without, however, the superoxid coming in a pure condition into the hands of the user, because on the one hand in a pulverulent or dusty condition it has a highly irritant action on the breathing organs and on the other hand in contact with moist organic substances—such as flour, sugar, paper, and the like—it is liable to spontaneous combustion.

Now this invention has for its object to make sodium superoxid as a very mild and yet powerful bleaching agent in combination with pure soap powder applicable as washing-powder for general use, while of course the liability to spontaneous combustion, the caustic or irritant action, and the liability to decompose must be made innocuous without affecting in any way the industrial use of the product. This is done by storing or packing the superoxid and the substances to be mixed with it—such, for instance, as soap or soap and free fatty acid (and soap-forming or saponaceous substances)—in a closed vessel provided with several separate compartments

in such a way that the separate compartments of the vessel containing the constituents of the washing-powder are arranged in such a way relative to one another that simultaneously with the opening of the package or vessel the contents of the separate compartments are compulsorily mixed in order that the superoxid in a pure condition may never reach the hands of the user unmixed. At the same time this method of packing has the advantage that the superoxid retains its entire contents of active oxygen and full effectiveness when mixed with soap.

A form of construction of a containing and packing vessel based on the principle hereinbefore developed is shown as an example in the accompanying drawings, in which—

Figure 1 is a vertical central section, and Fig. 2 a horizontal section on the line *x* *x* of Fig. 1.

An external, preferably cylindrical, vessel *a*, which concentrically incloses a tube *b*, preferably open at the bottom, in which the superoxid is placed, serves for receiving the soap powder. The tube *b* is attached to the lid or cover *c*, so that when the lid or cover is lifted off the pipe is drawn out with it and discharged. An expelling or discharging appliance *d* is attached, by means of a wire *e*, to the bottom *f* of the vessel *a* and expels the superoxid when the pipe *b* is drawn out, a rotary motion being imparted to the expeller, if desired, by hand.

The charging of the packing vessel is done before the bottom *f* is put on. The vessel *a* is placed upside down with its lid secured or closed, and the expelling device *d* is inserted in the tube, after which the outer compartment of the vessel is filled with soap powder or a mixture of soap and stearic acid and the inner pipe *b* with superoxid. The bottom *f* is then put on, which has a hole for the passage of the wire *e* and fits, by means of its projecting parts, into the vessel *a* and the pipe *b*. The bottom *f* extends, as shown in full lines in Fig. 1, all round the vessel *a* as an edge or rim. This projecting edge or rim is then folded over or bent round and the end of the wire *e* bent round and soldered down, as shown in dotted lines. The packing is now completed.

If it be desired to repeatedly use the package or container, the bottom *f* is only provided with a projecting part at the edge and the tube *b* is removably attached to the lid *c*—

for instance, by means of a bayonet-joint or the like—so that the box may be filled from above.

What I claim is—

- 5 1. A receptacle for packing and storing washing-powder containing an alkali super-oxid consisting of an outer vessel, a removable cover therefor and an inner vessel depending from said cover and removable therewith, the lower end of said inner vessel being normally closed by the bottom of the outer vessel.
- 10 2. A receptacle for packing and storing

washing - powder, consisting of a vessel, a cover therefor, a tube connected to the cover 15 and said tube having its lower end open, an expeller in said tube and a wire connected to the expeller and extending through the bottom of the vessel.

In testimony whereof I have signed my 20 name to this specification in the presence of two subscribing witnesses.

JULIUS VON KÖNIGSWARTER.
